ATTACHMENT FOR ELECTRIC-SWITCH DEVICES

1,136,255.

Specification of Letters Patent.

Patented Apr. 20, 1915.

Application filed November 15, 1911. Serial No. 600,343.

To all whom it may concern:

Be it known that I, CHARLES J. KLEIN, a citizen of the United States, residing at Milwaukee, in the county of Milwaukee and State of Wisconsin, have invented new and useful Improvements in Attachments for Electric-Switch Devices, of which the following is a full, clear, concise, and exact description, reference being had to the accompanying drawing, forming a part of this specification.

My invention relates to attachments for electric switch devices.

It has among its objects to provide an improved attachment for electric switch devices, provided with means for transforming an electric switch mechanism of the push button type into a switch mechanism of another type.

20 A further object of my invention is to provide an improved attachment for electric switch devices adapted to transform a switch mechanism of the push button type into a switch mechanism of the pull-chain type.

25 Other objects and advantages of my improved construction will hereinafter appear.

In the accompanying drawings I have, for purposes of illustration, shown two forms which my invention may assume in practice.

30 My invention is not, however, limited to these forms but may assume other forms.

In the views of these drawings: Figure 1 shows a side elevation of an electric lamp equipped with one form of my improved 35 switch actuating device. Figs. 2 and 3 show detailed views of this device. Fig. 4 shows the operating member of the device arranged in an angular position with respect to its support. Fig. 5 shows a modified 40 form of device. Fig. 6 shows a further modified form. Fig. 7 shows a side elevation of the construction shown in Fig. 6.

In the figures of the drawings I have, for purposes of illustration, shown my improved 45 switch actuating device applied to a single push button operated snap switch mechanism used in connection with an electric lamp. In this construction the lamp shell 1 is inclosed in a resilient band having a plurality of resilient arms 2, connected 50 together at one end as by means of a suitable screw or bolt 3, and, on the opposite side of the shell, an opening through which the push button 4 of the switch mechanism 55 extends. In this form the operating mem-

ber 5 is pivoted at 6 upon a pivot-supporting member 7, suitably swiveled around the opening in the band through which the push button extends, as by means of a rivet 8. Upon movement of the operating member 5 by means of a pull-chain, cord or other device 9, the operating member is moved about its pivot to force the push button 4 inward to make or break the circuit connections of the switch mechanism.

In a preferred form the band and arms 2 are formed of one strip of resilient metal which is provided with an enlarged portion 10 at a point approximately opposite the point where the arms are connected by the screw 3. This enlarged portion 10 may, in a preferred construction, be substantially circular in form, and cutaway portions 11 may be provided at the points where it is joined by the arms 2, in order to increase the 75 resiliency of the parts. In a preferred form the enlarged portion 10 has a concave inner surface as shown in Fig. 3, the edges of the same being inclined toward the lamp shell. In a preferred form the enlarged 80 portion 10 is provided with a central opening through which extends a suitable rivet or other device 8 having overturned edges arranged to clamp the pivot supporting member 7 to the inner surface of the enlarged 85 portion 10. This member 7 is preferably provided with an enlarged body portion 12 which, in a preferred form, has an irregular shaped periphery illustrated as substantially star-shape in Fig. 2. As in 90 the case of the enlarged portion 10, the portion 12 of the part 7 is also slightly concave to conform to the shape of the member 11. In a preferred form the concave portion 12 is connected to the portion 7 by 95 means of a neck 13 of slightly reduced width, which is so shaped that the portion 7 lies in a substantially parallel plane with the ends of the enlarged portion 10, permitting it to clear the flange on the lamp shell. The member 7 is preferably provided with a plurality of forwardly extending 100 parallel lugs 14, which are perforated near their ends to receive the pivot pin 6 about which the operating member 5 is moved. In a preferred form the operating member 5 is formed in the shape of a bell crank lever and made of a single piece of stamped metal. In a preferred form the inner end of the same is provided with an upper lug or 110

extension 15, which, when the operating member is in its up position, as shown in Figs. 1 and 3, rests against the member 7. The short inner arm of the bell crank member 5 is preferably provided with a cut-away portion 16 to permit a better grip upon the protruding end of the push button 4. The outer end of the other arm of the protruding member may be of any desired length and is, in a preferred form, twisted, as shown, in order to strengthen it and provide a suitable support for the end of the cord or chain 9. By the provision of the irregular shaped member 12 and the curvature of this member and the enlarged portion 10, I am able to provide a device which is very firmly held in position when the spring arms are attached to the support, since the inner surface of the member 10 binds against the inner surface of the irregular shaped member 12 and thus effectually prevents accidental rotation of this member and the operating member 5. If desired, by simply loosening the holding means 3 the operating member 5 may be arranged at any desired angle with respect to the arms 2, as shown in Fig. 4, so that the switch mechanism may be readily operated from any desired angle, the operating member being firmly held in any position to which it is moved by simply tightening the holding means 3.

When it is desired to operate a switch mechanism either to make or break the circuit all that it is necessary to do is to pull down or operate the lever 5 by means of the chain or cord 9. The operating member moves about its pivot 6, and the cutaway portion 16 on its lower arm engages with the protruding end of the push button. As the operating member is turned about its pivot this push button is pushed in to compress the springs within the switch mechanism, and at a predetermined point in its travel the switch mechanism is turned to make or break the circuit and the push button is returned to its normal position protruding from the shell. When the switch mechanism is thus returned to its normal position the operating member 5 is automatically swung backward by the push button about its pivot to the up-position shown in Fig. 1, so that it may be again operated by pulling down the cord or chain.

In Fig. 5 I have illustrated a modified form of actuating mechanism. In this construction I provide a disk 17 which may be formed of any suitable material and is arranged to be carried in substantially the same manner as the pivot carrying member 7, shown in Fig. 3. In this construction I preferably provide the disk 17 with an opening or slot 18 in its periphery, which is preferably slightly enlarged at its bottom, as shown in Fig. 5. This slot is ar-

ranged to receive the last bail or link of the chain 9, or, where a cord is used, the knot on the end of the cord. In this construction, instead of using a pivoted lever I provide a protruding cap 19 arranged to fit over the end of the push button. This cap 19 is preferably substantially cylindrical in shape and provided with a recessed end 20 arranged to receive and act as a guide for the chain or cord 9. In operating this device a pull upon the cord or chain, which has its ends fixed in the slot 18, acts to force in the cap 19, which is carried by the push button, to actuate the switch mechanism.

In Figs. 6 and 7 I have illustrated a modified form of this device, wherein I have provided a plurality of slots 18 upon the periphery of the disk, so that the switch mechanism may be operated from any desired angle by simply placing the end of the cord or chain in the desired slot. As in the previous construction, I preferably fit a cap 19 over the end of the push button 4 and mount the disk 17 in the same manner as described in connection with Fig. 5. In this construction the cap 19 is preferably provided with a plurality of recesses 20 in order to permit the cord to run through it in any position.

By the use of my improved attachment I am able to readily transform a push button operated switch mechanism into a switch mechanism of the pull-chain type. Further, by my improved construction I am able to provide a device which may be readily and conveniently arranged so that the switch mechanism may be operated by a pull from any desired angle. Further, by my improved construction I am able to prevent any accidental turning of the parts. Further, by the use of my improvement the switch mechanism is always actuated by a pull in the same direction in the same manner as a pull chain switch. The construction is an exceedingly simple one, and the device may be made of a small number of rugged parts at very small expense. Obviously, the cord or chain may be of any desired length, so that the switch mechanism may be located in any desired position and actuated with ease, when desired. By my improved construction there is no strain placed upon any of the operating parts, and the effort required to actuate the switch mechanism is very small.

What I claim as new and desire to secure by Letters Patent of the United States is as follows:

1. In combination, a lamp socket having a push button operating member for its switch mechanism, a band encircling the lamp socket and having an opening through which said push button extends, a support carried by said band and rotatable relatively thereto, said support also having an opening 130

through which said push button extends, and means attached to said support and engaging the end of said push button for operating the latter by operation of said means, 5 said means being rotatable with said support and being operable by pull.

2. In combination, a lamp socket having a single push button protruding therefrom, a band encircling said lamp socket and having 10 an opening through which said push button extends, a support carried by said band and angularly adjustable with respect thereto, and a bell crank lever pivoted to said support and having one end of the same normally 15 in engagement with said push button.

3. In combination, a push button operated snap switch mechanism, a support therefor, a band fixed to said support and having an opening through which a push button extends, a supporting member swiveled to said band and angularly adjustable with respect thereto, a bell crank lever pivoted to said support and limited in its movement in one direction by the latter, said bell crank lever 25 having one end of the same continuously in engagement with said push button.

4. In combination, a lamp socket, a push button operated snap switch mechanism carried therein having a push button protruding therefrom, a band fixed to said lamp socket and having an opening through which said push button extends, a supporting member swiveled to said band around the periph-

ery of said opening and adjustable in a plurality of positions, and a bell crank lever 35 pivoted to said support, said bell crank lever having one end of the same in continuous engagement with said push button and being operable to reciprocate said push button upon depression of its opposite end and to 40 be returned to its initial position upon the opposite reciprocation of said push button.

5. In combination, a lamp socket, a snap switch mechanism having a push button protruding therefrom, a band removably attached to said lamp socket and having an opening through which said push button extends, a support having a plurality of projections thereon, and an opening therein registering with the opening in said band, said support being swiveled to said band and angularly adjustable with respect thereto, a bell crank lever pivoted in laterally disposed lugs on one end of said support and limited in its movement in one direction by engagement with said support, said bell crank lever having one end in engagement with said push button and a pull chain attached to the opposite end of said bell crank lever. 55

In witness whereof, I have hereunto subscribed my name in the presence of two witnesses.

CHARLES J. KLEIN.
